UNITED STATES PATENT OFFICE.

ALBERT GANGWISCH, OF BREMERTON, WASHINGTON.

LEAF-TURNER.

1,354,820.

Specification of Letters Patent.

Patented Oct. 5, 1920.

Application filed May 21, 1919. Serial No. 298,739.

To all whom it may concern:

Be it known that I, ALBERT GANGWISCH, a citizen of the United States, residing at Bremerton, in the county of Kitsap and 5 State of Washington, have invented certain new and useful Improvements in Leaf-Turners, of which the following is a specification, reference being had to the accompanying drawings.

10 This invention relates to devices for turning the leaves of books, music, etc., and particularly to that class of turning devices wherein there are provided a number of leaf engaging arms rotated in one direction 15 by springs and attachable to the several leaves, these arms being released one by one whenever it is desired to turn a leaf.

The general object of my invention is to provide a very simple construction for this 20 purpose having few parts and being entirely effective in actual practice.

A further object is to provide very simple means for releasing the spring arms one by one to cause the turning of the leaf.

25 Other objects will appear in the course of the following description.

My invention is illustrated in the accompanying drawings, wherein:—

Figure 1 is a plan view of a leaf turner 30 constructed in accordance with my invention;

Fig. 1^a is a fragmentary view showing the actuating member 19 shifted from the position shown in Fig. 1;

35 Fig. 2 is a section on the line 2—2 of Fig. 1;

Fig. 3 is a sectional view on the line 3—3 of Fig. 4;

40 Fig. 4 is a section on the line 4—4 of Fig. 3; and

Fig. 5 is a section on the line 5—5 of Fig. 1.

Referring to these drawings, it will be seen that my music leaf turner comprises a 45 relatively small metallic base 10, which will be approximately $\frac{3}{4}$ " wide and $\frac{1}{6}$ " thick, and sufficiently long to reach across the book or music when the latter is open. Mounted upon the middle of the base 10 is

50 an approximately semi-circular housing 11 having opposed side walls and inwardly extending flanges to leave an opening 12 extending through this housing. A rod 13 is attached to the housing and base and extends rearward therefrom, and is adapted to lie against the middle leaf of the book or

music. Preferably, though not necessarily, a small metallic strip 14 will be attached to the strip 10 and extend therefrom at right angles and beneath the rod 13. Spring 60 clamps 15 will be attached to the rear face of the base adjacent the opposite ends thereof, these clamps being formed with opposed jaws adapted to engage the covers or fly leaves C of the book or music and hold them 65 flat to the base and the book or music in an open position.

Mounted upon the rod 13 are a plurality of arms 16. Each of these arms is rotatably mounted on the rod 13 at one end and is 70 engaged by a coiled spring 17 which urges the corresponding arm or rod 16 from right to left. Each of these arms 16 carries a leaf engaging clamp 18 which may be adjustable upon the arm so as to engage leaves 75 L of different size.

Pivottally mounted upon the base 10 is a locking and releasing member 19 having an operating arm 20 extending therefrom, this member 19 being formed to provide 80 two detent teeth 21 and 22 disposed in different vertical planes. When the operating arm 20 is in the position shown in Fig. 1, the detent 22 will engage the outermost leaf turning arm 16 and hold it from 85 rotation under the action of its spring. When the operating arm 20 is shifted to the position shown in Fig. 1^a, the detent 22 will release the outermost arm 16, but before this happens, the detent 21 will engage the 90 next arm below, so that one arm is released and the other arms are still held from actuation by their springs. Upon a release of the operating arm 20, it will swing back to its normal position, as shown in Fig. 1, and 95 the detent 22 will again engage the outermost arm to prevent its movement until the operating arm 20 is again actuated. It will be seen that this is a very simple means for releasing the leaf turning arms one by one, 100 and that in order to release an arm to turn a leaf, it is only necessary for the reader to move the arm 20 inward by a slight movement of his finger, whereupon the parts will be released, as before described. The 105 arm 20 can be positively shifted outward by a spring.

While I have illustrated a form of my invention which I believe to be particularly effective in practice, it will be obvious that 110 many changes might be made in the details of construction and arrangement of parts

without departing from the spirit of the invention. My device is light, it is very portable, it may be easily applied, and can be used with any desired base or merely 5 rested upon a table or stand, and the parts may be readily made so that the whole device can be folded up and taken apart and carried in the pocket.

I claim:—

- 10 A music leaf turner comprising, an elongated horizontal strip provided with clamping means adjacent its opposite ends and secured to the rear face thereof, a housing extending outwardly from the front face 15 of said strip and substantially at the longitudinal center thereof, said housing embodying spaced opposed side walls provided with inwardly extending flanges, said flanges having their adjacent face spaced to 20 afford a slot extending longitudinally with relation to said strip, a vertically disposed

rod having its lower end mounted in the side walls of said housing, leaf turning arms supported by the portion of the rod within the housing for swinging motion in 25 the horizontal plane, spring means coacting with each of said arms for imparting swinging movement thereto in one direction, means carried by the strip for holding the arms in one position and successively 30 releasing the arms, leaf engaging-clips longitudinally adjustable upon said arms and a member carried by the strip at substantially its longitudinal center and disposed in the same general direction as said rod. 35

In testimony whereof I hereunto affix my signature in the presence of two witnesses.

ALBERT GANGWISCH.
